H. S. WILLIS,
TROUSERS CRESSING DEVICE,
APPLICATION FILED SEPT. 17, 1920.

1,409,633.

Patented Mar. 14, 1922.

UNITED STATES PATENT OFFICE.

HERMAN S. WILLIS, OF WILMINGTON, DELAWARE.

TRousERS-CREASING DEVICE.

1,409,633.

Specification of Letters Patent. Patented Mar. 14, 1922.

Application filed September 17, 1920. Serial No. 411,002.

To all whom it may concern:

Be it known that I, HERMAN S. WILLIS, citizen of the United States, residing at Wilmington, in the county of New Castle and 5 State of Delaware, have invented certain new and useful Improvements in Trouser-Creasing Devices, of which the following is a specification.

This invention relates to improvements in

- 10 a trousers creasing device and its main object is to provide a device of this character by which a pair of trousers may be creased without necessitating the removal from the wearer.
- 15 A further object of the invention is to provide an improved device of the above character which is simple in construction, one which can be quickly and easily operated and one which can be manufactured and sold
- 20 at a reasonably low cost.

A still further object of the invention is to provide a trousers recreasing device which includes an attachment for creasing coat sleeves and the like.

- 25 Various other objects and advantages of my invention will become apparent during the continuance of the following description.

In the drawings:

- 30 Figure 1 is a view in perspective showing the trousers creasing device as in actual operation.

Figure 2 is a view in front elevation of a portion of the trousers recreasing device.

- 35 Figure 3 is a view in horizontal cross section taken on line 3—3 of Figure 2.

Figure 4 is a view in side elevation of another part of the creasing device.

- 40 Figure 5 is a view in front elevation of that part of the creasing device shown in elevation in Figure 4 and

Figure 6 is a view in perspective of an attachment for the trousers recreasing device to be used in creasing coat sleeves, etc.

- 45 In reducing my invention to practice I first provide a suitable base or carrying portion 10 which is substantially inverted U-shaped when viewed in front elevation as in Figure 2 and which includes lugs 11 at its

- 50 lower end which may be secured to the floor or other support 12 as at 13. At its upper end the portion 10 is provided with a socket 14 in which operates a set screw 15, the purpose of the latter being fully described hereinafter.

I also find it expedient to provide a metal-

lic rod or bar 16 which is so formed so as to taper to a fine leading edge 17 the same being substantially V-shaped when viewed in cross section as in Figure 3. The lower 60 end of the rod or bar 16 sets into the socket 14 of the member 10 as shown in Figure 2 and by tightening the set screw 15 the same is securely held in place. When in actual practice the foot of the wearer of the trousers is inserted through the arch portion of the member 10 as shown in Figure 6 while the rod or bar 16 extends inside the trousers so that the even edge 17 thereof is directly 65 behind the front crease of the trousers or a point at which the front crease is to be made. For holding the trousers in place on the rod or bar 16 I find it expedient to provide suitable spring clips such as shown at 18.

The iron used in connection with the rod 75 or bar 16 includes an electrically heated disc or roller 19 having a substantially V-shaped peripheral groove 20 to fit the leading edge 17 of the rod or bar 16 and is carried upon arms 21 which terminate in a handle portion 80 22. A suitable electrical connection as shown at 23 may be had with the handle 22 from a suitable source of power.

When the device is in the position shown in Figure 1 the iron 19 is simply run up and 85 down the trousers leg so as to form a straight and accurate crease. The operation is extremely simple and it can be readily seen that the trousers leg may be creased without necessitating the removal from the wearer. 90

Upon reference to Figure 2 it will be observed that the upper end of the rod or bar portion 16 is provided with an extension 24. When it is desired to crease the sleeve of a coat, etc., the rod or bar portion 25 is used 95 which includes a socket 26 at its lower end to receive the reduced extension 24 of the rod or bar portion 16. The rod or bar portion 25 is simply inserted in the sleeve of the coat and the iron 19 moved thereover similar to the creasing operation of the trousers leg. 100

From the foregoing it is believed that the advantages and novel features of my invention will be readily understood and therefore 105 further detailed description is deemed unnecessary.

What is claimed is:

1. In a creasing device for trousers, a supporting stand, substantially inverted U-shaped when viewed in front elevation, a socket carried by said stand, a rod substan-

- tially V-shaped when viewed in cross section, having one end in said socket, means to retain said rod in place in said socket, said rod adapted to fit within one leg of a pair of trousers, means to retain said rod in position within said trousers leg, said rod adapted to cooperate with an iron on the outside of the trousers leg to crease said trousers leg substantially as described.
- 10 2. In a creasing device for trousers, a supporting stand, substantially inverted U-shaped when viewed in front elevation, a socket carried by said stand, a rod substantially V-shaped when viewed in cross section and having a fine leading edge, one end of said rod being positioned within said socket, means carried by said socket to retain the rod in place, said rod adapted to fit within the trousers leg, means to retain said rod in place in said trousers leg, said rod adapted

to cooperate with an iron on the outside of the said trousers leg and bearing against the said leading edge of the rod to crease said trousers, substantially as described.

3. A creasing device comprising a stand, 25 substantially inverted U-shape in front elevation and provided with a socket, a creasing rod of detachably connected sections respectively adapted to be placed within a trousers leg and a coat sleeve, means for fastening one end of the said rod in said socket, means for retaining the sections of the rod in place within the trousers leg and coat sleeve, said rod sections being substantially V-shaped in cross section and adapted to cooperate with an iron on the outside of the leg and sleeve to crease the latter substantially as described.

In testimony whereof I affix my signature.
HERMAN S. WILLIS.
